UNITED STATES PATENT OFFICE.

WILLIAM G. BLACK, OF NEW YORK, N. Y.

DESIGN FOR A BOTTLE.

SPECIFICATION forming part of Design No. 17,504, dated August 2, 1887.

Application filed April 12, 1887. Serial No. 234,553. Term of patent 7 years.

To all whom it may concern:

Be it known that I, WILLIAM G. BLACK, a resident of the city, county, and State of New York, have invented and produced a new and original Design for Bottles, of which the following is a specification, reference being had to the accompanying drawings, forming part thereof, in which—

Figure 1 represents a face view of my newly designed bottle, and Fig. 2 represents an edge-wise view of the same.

The bottle is formed, as shown, with curves from the base-line to the neck on all sides and edges, so as to present an arched contour; and the neck is of considerable length, extending from the top of the arch, and ornamented with three rings or moldings encircling it, distinctly separated from each other, so as to be readily noticeable.

On the one face (shown in Fig. 1) is a representation of a woman's head with long flowing hair or tresses, the head at one side, so that the hair reaches backward across (or nearly) the face of the bottle.

A represents the base line of the bottle. B 25 represents the lines of the body extending upward from the base-line and arching toward the neck, curving the entire distance. C represents the neck, and D, E, and F the three rings or moldings. G represents the female 30 head on the face of the bottle, and H the flowing hair or tresses.

What I claim as new, and desire to secure by Letters Patent, is—

The design for a bottle, as herein shown and 35 described, the same having an arched contour upward from its base, with a neck ornamented by three rings or moldings, and having on its face, below the neck, the representation of a female head with flowing hair, essentially as 40 shown and described.

WILLIAM G. BLACK.
